UNITED STATES PATENT OFFICE.

FRANK EVORY MENDENHALL, OF KILGORE, NEBRASKA.

POTATO-PLANTER.

1,321,226.

Specification of Letters Patent.

Patented Nov. 11, 1919.

Original application filed January 23, 1917, Serial No. 143,927. Divided and this application filed March 15, 1918. Serial No. 222,759.

To all whom it may concern:

Be it known that I, FRANK EVORY MENDENHALL, a citizen of the United States, and a resident of Kilgore, in the county of 5 Cherry and State of Nebraska, have invented certain new and useful Improvements in Potato-Planters, of which the following is a specification.

My invention is an improvement in potato 10 planters, and has for its object to provide mechanism for taking the cuts from a hopper and delivering them one by one into a leg or dropper chute.

In the drawings:

15 Figure 1 is a longitudinal section through the planter of which the wheel is a part, with parts omitted for the sake of clearness;

Fig. 2 is a side view of the fork supporting member of the dropping wheel from the 20 inside, with parts broken away;

Fig. 3 is a section on the line 3—3 of Fig. 2, looking in the direction of the arrows adjacent the line;

Fig. 4 is a view from the inside of the 25 operating cam for the impaling forks;

Fig. 5 is a perspective view of one of the said forks.

The embodiment of the invention shown 30 in the present application, which is a division of my prior application Serial No. 143,927, is shown in connection with a planter comprising a frame consisting of an arch bar 1 having openings in its arms through which passes the axle 2, and the dropping 35 wheel, to be described, is keyed to the axle between the wheels 7 which are secured to the ends of the axle.

A tongue 5 is connected with the arch bar and a hopper 32 is arranged behind the axle, 40 being supported by the tongue as shown.

The dropping wheel, as shown more particularly in Figs. 2, 3, 4 and 5, consists of sections 18 and 19, respectively, each section having a hub which extends to the adjacent arm of the arch bar, thus spacing the dropping wheel sections at the center of the axle. The section 18 is secured to the axle 2 by means of a key 20 and a set screw 21, while the section 19 is free to rotate on the 50 axle. The section 18 of the dropping wheel is a cam having on the inner face thereof a cam groove 22, and the wheel is provided with a counterbored or reamed opening 23 at one part of the groove, for a purpose to

55 be later mentioned.

The section 19 is provided in its inner face with an annular groove 24 intermediate the shaft 2 and the periphery of the wheel, and from this annular groove lead grooves 25 to the periphery of the section. The grooves 60 25 are tangential to the inner wall of the annular groove, and in each of the tangential grooves is arranged a slide bar 26 which carries an impaling fork 27. The slide bars fit smoothly in the grooves, and 65 they are moved by means of rollers 28 journaled on the bars and engaging the groove 22 of the cam section 18. The groove 22 is so arranged that as the impaling forks approach the hopper, to be later described, the 70 slide bars will be moved outwardly by means of rollers 28 which are journaled on the slide bars, and which engage in the groove 22 of the cam.

The slides are held in their grooves by 75 means of a holding ring 29 which is secured to the face of the section 19 by screws or the like, and this holding ring has inclined slots 30 through which the rollers 28 extend in engagement with the cam groove. 80 Through the opening 23 the rollers may be oiled and cleaned, and the slots 30 permit the free movement of the rollers and slide bars. It will be noticed that the tines of the impaling forks are curved or arched and 85 that the said tines of each fork are parallel with each other, so that the tendency of the forks to pick up more than a single cut is reduced to a minimum. The dropping 90 forks take the cuts from the extension 31 of the feed hopper 32 which is secured to the rear end of the tongue. The extension is merely an open trough having a slot in its bottom through which the impaling forks may pass, and the hopper at the feed opening which is at the extension is provided with an adjustable door 33 for varying the extent of the feed opening. This door is adjusted by means of bolts 34 which pass through registering opening in the hopper 100 and slots in the feed door, and the bolts are engaged by nuts to clamp the door to the feed hopper.

The impaling forks impale the cuts as 105 they are moving up about the rear side of the dropping wheel, and they drop them as they are moved down on the front side of the dropping wheel into a leg or feed chute 35 which is supported in front of the dropping wheel, and has an opening in its rear 110

into which the dropping wheel extends. The drawing in of the forks by the cam positively dislodges the cuts.

Means is provided for dislodging cuts that 5 might be picked up by the impaling forks without being impaled, that is, that might be held in the curve of the tines. The said means comprises a spring finger 68 which is secured to a bracket 69 on the cam portion 18 of the dropping wheel. This finger extends into the path of movement of the forks and will dislodge any cuts that might be carried up by the fork without being impaled.

15 In operation, the potato cuts are placed in the feed hopper, as shown, and the feed opening of the hopper is regulated so that a number of cuts will lie upon the extension 31 without falling off. As the machine 20 moves forwardly, the dropping wheel will be rotated and the impaling forks 27 will pass in succession through the extension hopper, and each fork will take up a single cut. As the forks pass over to the front of 25 the wheel and down the same the cuts are dislodged as the forks withdraw and will fall into the chute, which will deliver them into the furrow.

I claim:

30 1. In a potato planter, a dropping wheel having passages opening at the periphery of the wheel tangential to a circle concentric with the axis of the wheel, slides in the passages, each slide having an impaling fork 35 at its outer end for impaling a potato cut when the fork is extended, the cut being dislodged when the fork is withdrawn, means for moving the slides and means for delivering the cuts to the forks when they are 40 extended.

45 2. In a potato planter, a dropping wheel having passages therein tangential to a circle concentric with the axis of the wheel, and opening at the periphery of the wheel, slides in the passages, each slide having an impaling fork at its outer end for impaling a potato cut when the fork is extended, the 50 cut being dislodged when the fork is withdrawn, the tines of the fork being curved in the direction of rotation of the wheel, means for delivering cuts to the forks when they

are extended, and means for removing from a fork a cut engaged but not impaled thereon.

3. In a potato planter comprising a wheel supported frame and a hopper supported on 55 said frame, said hopper being provided at its lower extremity with an extension shelf having a slot formed therein and being further provided with an opening permitting cut potatoes within the hopper to pass onto 60 said extension shelf, and a dropping wheel having slides movable therein and carrying at their outer ends impaling forks adapted to pass through the slot in said extension shelf whereby to impale the potato cuts 65 thereon.

4. In a potato planter, a dropping wheel comprising a disk member having formed therein a concentric annular recess and further provided with a plurality of passages 70 opening at the periphery of the disk and extending tangentially to and communicating with said concentric annular recess, a slide disposed within each passage and carrying at its end an impaling fork, a roller on 75 each slide intermediate the ends thereof, a circular plate secured upon said disk and covering said concentric annular recess and retaining said slides in position, said plate being provided with slots disposed in registration with said passages and permitting 80 sliding movement of said rollers, the rollers extending through said slots, and a second disk member disposed against said plate and provided upon its face with a cam 85 groove receiving said rollers whereby upon relative rotation of said disks said slides will be moved to successively expand and retract the forks carried thereby.

5. In a potato planter, a dropping wheel 90 carrying a plurality of impaling forks each including spaced tines, means for supplying potato cuts into position to be impaled by said forks, and a spring finger disposed in the path of travel of said forks whereby to 95 disengage therefrom a cut disposed but not impaled thereon.

FRANK EVORY MENDENHALL.
